UNITED STATES PATENT OFFICE

HAROLD CARLSON, OF NORTH FRANKLIN, CONNECTICUT

PICKER STICK BUFFER

Application filed October 3, 1930. Serial No. 486,273.

This invention relates to looms, and more particularly to a device designed to check or retard the movement of the picker stick of the loom, to prevent breaking or damaging 5 the picker stick by its contact with the lay, at the end of the stroke of the picker stick.

An important object of the invention is to provide a device of this character which may be readily and easily secured in position on 10 a loom, without the necessity of making extensive alterations in the loom construction, to mount the attachment.

With the foregoing and other objects in view, which will appear as the description 15 proceeds, the invention resides in the combination and arrangement of parts and in the details of construction hereinafter described and claimed, it being understood that changes in the precise embodiment of the invention 20 herein disclosed, may be made within the scope of what is claimed, without departing from the spirit of the invention.

Referring to the drawings:

Figure 1 is a side elevational view illustrating the lay of a loom as equipped with a device constructed in accordance with the invention.

Figure 2 is a rear elevational view thereof.

Figure 3 is a plan view.

Figure 4 is a bottom plan view of a lay equipped with a device constructed in accordance with the invention.

Figure 5 is a fragmental elevational view 35 of a picker stick equipped with a spring or cushion device.

Figure 6 is a front elevational view of the picker stick.

Figure 7 is a fragmental elevational view of 40 a picker stick illustrating the means for securing the power strap to the picker stick.

Figure 8 is a sectional view through the picker stick, taken on line 8—8 of Figure 7.

Referring to the drawings in detail, the 45 reference character 5 designates the lay of a loom which is formed with the usual slot to receive the picker stick 6 of the loom.

The picker stick check or buffer, forming 50 the essence of the present invention, comprises elongated bracket members 7 arranged

on opposite sides of the slot in the lay, through which the picker stick moves.

These bracket members 7 are formed with depending end portions 8 and 9 respectively, which end portions are formed with openings 65 to receive the U shaped check or buffer 10, which is constructed of a length of rod material bent to provide an end section 11 that spans the space between the end portions 9. Strips of leather or other cushioning material indicated at 12, are positioned near the end section 11 to be engaged by the picker stick 6, when it moves to the limit of its stroke, in one direction.

Adjustably mounted on the buffer 10, are 65 stops 13 against which the coiled springs 14 engage, the opposite ends of the coiled springs resting against the end portions 9, so that the buffer 10 may move against the tension of the springs, the springs yielding under the 70 action of the picker stick to cushion the movement of the picker stick.

The depending end members 8 are also formed with openings to receive the buffer 15 that comprises a length of rod material bent 75 intermediate its ends to provide spaced leg members that have their forward ends secured within the openings, by means of nuts 16.

Mounted on the leg members of the buffer 80 15, are coiled springs 17 that bear against the bar 18 mounted on the leg members, the coiled springs 17 also engaging the bar 19 that is slidably mounted on the leg members of the buffer.

This bar 19 lies in the path of travel of the picker stick as it reaches one end of its stroke, the force of the picker stick being cushioned by the movement of the bar 19 against the springs 17 that yield under the 90 action of the picker stick.

To further cushion the movements of the picker stick, a spring member indicated by the reference character 20 is provided, one end of the spring member being secured adjacent to the outer end of the picker stick, the opposite end thereof being slidably held by means of the U bolt 21. The central portion of the spring 20 is bowed to lie in spaced relation with the rear edge of the picker stick 100

to cushion the movements of the picker stick to which it is secured, when the picker stick moves to the limit of one end of its stroke.

From the foregoing it will be obvious that due to the construction shown and described, the movements of the picker stick of a loom may be cushioned to relieve the picker stick of the sudden jar caused by the picker stick being suddenly stopped at the ends of its stroke, to the end that the life of a picker stick is greatly increased.

Secured to the picker stick is a power strap attaching device comprising a body portion 22 which is formed with cut out portions of widths to receive the power strap 23, the cut out portions defining shoulders 24 to engage the upper and lower edges of the power strap and prevent the power strap moving out of its place on the picker stick.

20 I claim:

A picker stick check for looms, comprising a pair of elongated bracket members formed with depending end portions, said bracket members being secured to one side of the lay 25 of a loom and on opposite sides of the picker stick slot of the lay, a rod bent intermediate its ends and providing parallel legs, extended through the depending end portions of the bracket members, coiled springs adjustably 30 mounted on the leg members and bearing against one of the depending ends of the respective bracket members, the intermediate portion of the rod spanning the space between the depending end members at one end of 35 the bracket members providing a stop to be engaged by the picker stick, a rod bent intermediate its ends providing a substantially U-shaped stop, the ends of the rod being secured to the opposite depending end members 40 of the bracket members to provide a stop, and coiled springs on the last mentioned stop for cushioning the movements of the picker stick.

In testimony that I claim the foregoing as 45 my own, I have hereto affixed my signature.

HAROLD CARLSON.
